UNITED STATES PATENT OFFICE

LLOYD E. JACKSON, OF PITTSBURGH, PENNSYLVANIA

DRY CLEANING

No Drawing.

Application filed April 8, 1929. Serial No. 353,685.

My invention relates to the process of dry cleaning commonly employed in the cleaning of fabrics, and consists in such control of the composition of the cleaning materials as will 5 avoid certain objectionable features or characteristics of the process as it ordinarily is conducted.

In the usual process of dry cleaning such articles as garments and house furnishings 10 are placed in washing machines together with petroleum naphtha and agitated. The washing machines are of different designs, but a common type consists of a hollow cylinder made of either slats of wood or perforated 15 wood or metal, mounted horizontally on trunnions and enclosed in a wood or metal shell. Naphtha put into the washer is retained by the outer shell. The hollow cylinder and the outer shell are fitted with suitable doors so that the articles may be placed 20 in and removed from the cylinder. The cylinder when in operation is mechanically rotated back and forth, a few turns one direction, and a few turns the opposite direction 25 alternately. The agitation produced in this manner causes the dirt to be removed by the naphtha from the articles.

The major portion of the dirt in the articles is easily removed. Some of the soil, food 30 spots, etc., however, may remain, and these can be removed only with the aid of special detergents. Dry-cleaning soap is used for this purpose. There are two distinct types of dry-cleaning soap used in practice. One type 35 contains a mixture of partially saponified fatty acids, organic solvents, and water; the other type contains a mixture of completely saponified fatty acids, organic solvents, and water. The alkali commonly used for saponifying the fatty acids may be either any one of, or a mixture of, the following: sodium 40 hydroxide, potassium hydroxide, ammonium hydroxide, sodium carbonate, potassium carbonate, ammonium carbonate, sodium 45 aluminate. Other alkaline substance which will produce saponification of the fatty acid may be used to prepare the dry-cleaning soap.

Dry cleaning may be conducted as a batch process or as a continuous process. The 50 batch method consists of introducing the

soiled articles to be cleaned into a measured batch of naphtha in a washer, and then operating the washer for a period of time, usually from 5 to 30 minutes. After the run in the washer the naphtha and the dirt and dissolved matter it contains are removed from the washer. In some dry-cleaning plants a run of a given quantity of articles in two batches of naphtha successively is considered sufficient; in other plants the materials may 55 be subjected to treatment in fresh batches of naphtha ranging from one to six in number. Dry-cleaning soap is usually added either to the first or to the second batch of naphtha, and sometimes to the second and third 60 batches. After the articles have been given what is considered a sufficient number of runs in the washer, they are removed from the washer and placed in a centrifugal extractor, 65 where the major portion of the naphtha contained in them is removed. The remaining naphtha may then be removed by allowing the articles to hang in heated rooms, or by placing them in drying-tumblers. Finally, any 70 spots not removed by the treatment in the washers are by additional, localized treatment removed and the articles are pressed or finished in some other suitable manner. The naphtha used in the batch method of cleaning 75 is collected as it is taken from the washer and it is recovered for use again by methods known to the industry.

In the continuous process the mechanical procedure is the same as in the batch method. The difference between the batch method and the continuous method is that in the latter one larger quantity of naphtha is caused to circulate through the washer, thence through a purifying apparatus, and then back into the washer again. In the purifying apparatus dirt and suspended matter are removed 80 and only clean naphtha is returned to the washer. The same volume of naphtha is used over and over again for cleaning successive loads of materials. Dry-cleaning soap of the 85 nature mentioned in the description of the batch method is usually used in the continuous process.

The purifying apparatus may consist of a still or of a caustic treating unit together 90

with a filter or a centrifugal clarifier or separator.

Fabrics of all sorts are so cleaned, whether they be of wool, silk, rayon, cotton, jute, 5 ramie, or other fibre; and other materials, not woven, as for example fur, feathers; in short, fibrous material of all sorts.

It has been found that dry-cleaned articles often acquire after a short period of 10 time—say of two or three weeks—a disagreeable, rancid odor; and this disagreeable odor has been found to be due to the oxidizing of fatty acids, traces of which present in the dry-cleaning soap, have remained in 15 the articles. In order to avoid this undesirable odor, it is becoming a practice in the dry-cleaning industry to use completely-saponified soaps containing no free fatty acid, especially in the continuous process of 20 cleaning. Even so the difficulty is not completely overcome, and the disagreeable odor may yet develop, in spite of preventive care.

When a completely saponified soap is used in continuous process, it is common practice 25 to use a method for purifying the naphtha during the continuous run in which only suspended matter is removed from it, leaving the soluble substances, including the dry-cleaning soap, in solution. The soapy bath 30 is used continuously to clean successive loads of materials. The materials are removed from the bath, centrifuged, and dried. The soap dissolved in the small amount of naphtha remaining in the materials after 35 centrifuging is left as a residue in them. The soapy bath is used over and over again and it is necessary to make small additions of soap with each load of materials cleaned.

I have discovered that the hitherto uncorrected difficulty is to be found in the articles 40 themselves; I have found that they often contain appreciable quantities of acid; that the acid so present, reacting with the soap will effect the release of free fatty acid, 45 even though initially saponification had been complete; and that the so released acid does in particular cases, and after repeated loads of material have been cleaned, become the immediate cause of a rancid odor. I 50 have discovered, furthermore, that by the decomposition of the soap and the gradual building up of free fatty acid in the bath, the detergent power of the soap is weakened and that some of the water in the dry-cleaning 55 soap is selectively absorbed by the textile materials, thus removing it from and reducing the detergent properties of the soap.

And I have found that, if a measured quantity of an alkali dissolved in water be added 60 to the cleaning bath after each load of materials has been cleaned, the free fatty acid liberated by the acids in the materials may be neutralized, and the requisite water re- 65 stored to the bath. It is quite important

that the quantity of alkali and water required for the purpose of rejuvenating the soap in the bath be carefully determined by a chemical test, and only such quantities of alkali and of water be added as will restore 70 the detergent power of the soap. If too much alkali be added it will coagulate the soap, with the result that soap will as the continuous operation progresses be removed from the bath. If too little alkali be added, 75 the full detergent value of the soap will not be restored. If too much water be added, it will both cause a flocculation of the soap and will cause the materials which are being cleaned to become wet with water.

I determine the quantity of alkali which will be required to neutralize the free fatty acids in the bath by titrating a measured quantity of the used soapy naphtha from the dry-cleaning bath with standard caustic 80 solution, by methods known to any chemist. In my experimental work a 100 c. c. portion of the used naphtha was titrated with 0.03 normal caustic soda solution in the presence of 50 c. c. of neutralized alcohol, using 85 phenolphthalein as an indicator. It was found that the alkali subsequently added to the bath should be no more or less than that required to keep the titration of 100 c. c. of the bath between 4 c. c. and 12 c. c. of 90 0.03 normal caustic solutions. If the bath 95 be so far neutralized that less than 4 c. c. are required for the titration, there is a tendency for the soap to flocculate, and in consequence to be removed from the bath 100 by the purification process; if the neutralization be so far incomplete that more than 12 c. c. are required for the titration, there is a needless waste of the possible detergent 105 power of the soap.

The alkali used for rejuvenating the soap in the dry-cleaning bath may be any of those previously mentioned as being suitable for the preparation of dry-cleaning soap.

The quantity of water required for rejuvenating the dry-cleaning soap, was determined by a series of distillations of the soapy dry-cleaning bath. The water required is proportional to the weight of materials cleaned. Approximately 1 quart of 110 water was found necessary for each 150 pounds of materials cleaned.

The following is a description of process as in consequence of my discovery and experimentation it is practiced commercially. 115 Four hundred gallons of petroleum naphtha are introduced into a system consisting of a washer, a purifying unit (which may be a filter or a centrifugal clarifier or separator), a pump, and pipes connecting these parts. 120 Three gallons of completely saponified soap are added to the naphtha. One hundred and fifty pounds of garments to be cleaned are placed in the washer. The washer is operated for 25 minutes, during which time the 125 130

soapy naphtha is pumped continuously from the washer to the purifying unit and back to the washer again. Near the end of the run, say after 20 minutes of operation, a 5 sample of the soapy naphtha is removed from the machine. 100 c. c. of the sample are measured and titrated with a 0.03 normal caustic soda solution. The quantity of caustic solution required for the test may be 10 7.0 c. c. Then as soon as the 25-minute run is completed, the cleaned garments are removed and another load weighting 150 pounds is introduced into the washer, when another 25-minute run is started. A pint 15 of potassium carbonate solution, prepared by dissolving 35 pounds of potassium carbonate in 16 gallons of water, and a pint of water are mixed together and poured into the washer while it is running. After 20 the second run has been in progress for 20 minutes a second sample of the soapy naphtha is removed. The titration on 100 c. c. of the sample may be 10 c. c. of 0.03 normal caustic solution. Then in the following run 25 2 pints of the caustic solution may be added to the washer. The titration on a 100 c. c. sample of the soapy naphtha after this run may be only 6 c. c. of 0.03 normal caustic soda solution. Then in the succeeding run 30 a half pint of the potassium carbonate solution and one and one-half pints of water may be added to the bath. In this manner the acidity of the cleaning bath is controlled, so that the titration on 100 c. c. of the bath 35 is kept between 4 c. c. and 12 c. c. of 0.03 normal caustic solution.

I claim as my invention:

1. In the operation of dry-cleaning by the repeated application of soap-bearing naphtha the method herein described of restoring 40 to the used naphtha its detergent power which consists in testing quantitatively for free acid a sample taken from such body of used soap-bearing naphtha, and adding 45 alkali to the body of used soap-bearing naphtha in quantities sufficient to saponify completely all free fatty acid, as determined by such testing.

2. In the operation of dry-cleaning in continuous manner the method herein described 50 of maintaining the quality of the circulating stream of soap-bearing naphtha which consists in testing quantitatively for free acid a sample taken from the circulating stream 55 after the cleaning operation has been in progress, and adding alkali to the stream in quantity sufficient to restore the naphtha to its original condition as determined by such test.

3. In the operation of dry-cleaning in continuous manner the method herein described 60 of maintaining the quality of the circulating stream of soap-bearing naphtha which consists in testing quantitatively for free acid and for water samples taken from the cir-

culating stream after the cleaning operation has been in progress, and adding to the stream alkali and water in quantities sufficient to restore the naphtha to its original condition as determined by such testing.

4. In the operation of dry-cleaning by the repeated application of soap-bearing naphtha, the method herein described of restoring 70 to the used naphtha its detergent power which consists in testing quantitatively for free acid and for water a sample taken from such body of used soap-bearing naphtha and adding alkali and water in quantities 75 sufficient to restore the body of used soap-bearing naphtha to its original condition, as 80 determined by such testing.

In testimony whereof I have hereunto set my hand.
